TANGLE-PROOF ELECTRODE COIL FOR
ELECTRIC DISCHARGE DEVICE

Thomas A. Hoffmann, Morris Plains, and Thomas H. Heine, Cedar Grove, N.J., assignors to Westinghouse Electric Corporation, East Pittsburgh, Pa., a corporation of Pennsylvania

Filed July 26, 1962, Ser. No. 212,539
6 Claims. (Cl. 313—341)

This invention relates to discharge devices and, more specifically, to an improved electrode for a rapid-start fluorescent lamp.

In order to reduce the wattage dissipated in the electrodes of so-called "rapid-start" fluorescent lamps during normal operation, the size of the electrodes is reduced by decreasing the number of secondary or major turns in the coiled coil. Since the preheating current in such lamps flows through the electrodes continuously after the lamp has been started and is normally operating, the size or mass of the electrodes must be decreased in order to keep the wattage dissipated by the electrodes during normal operation within acceptable limits. Such rapid-start fluorescent lamp electrodes accordingly consist of a coiled coil that have approximately three secondary or major turns and long legs that extended axially outward from each end of the coil barrel. The prior art rapid-start electrodes which embody this design are shown in FIGS. 1 to 3 of the accompanying drawing and are described in detail in U.S. Patent No. 2,774,918 issued December 18, 1956, to E. Lemmers.

The aforesaid problem does not arise in the case of conventional or so-called "preheat" type fluorescent lamps since the preheating current is automatically terminated, after starting, by a glow switch or the like.

When attempts were made to reduce the manufacturing cost of such rapid-start fluorescent lamps by automatically feeding the electrodes into the stem-making machine, it was found that the coils had a tendency to tangle and would not separate when placed into the hopper of an automatic feeding unit. In such units the hopper is mechanically vibrated in such a manner that the coils in the hopper "walk up" a helical track that is wide enough to hold only a single coil. The coils are, accordingly, fed one at a time from the track into a suitable transfer device, and then into the stem-making machine.

It was found that the tangling was due to the fact that when a pair of coils become axially aligned the leg of one coil would enter the short barrel of the other coil, and vice versa, thus causing the coils to become interlocked. Moreover, since the coil barrel was short and was terminated by long legs at each end, such rapid-start electrodes were inherently unstable when placed on a flat surface. Thus, even those that were not interlocked tended to wobble along the track of the feeding unit and frequently fell back into the hopper further complicating the coil-feeding problem.

It is accordingly the general object of the present invention to provide an improved electrode coil for an electric discharge device which can be automatically handled and fed into a mounting machine.

Another and more specific object is the provision of a coiled electrode for a rapid-start fluorescent lamp, which electrode can be automatically transferred into the stem-making machine and has substantially the same electrical characteristics as the electrodes employed heretofore.

The aforesaid objects and other advantages are realized according to this invention by forming an additional turn at each end of the coiled coil, which turn is wound at a much greater pitch than the major turns which comprise the coil barrel. The axially extending legs are, accord-

2

ingly, very short and are automatically prevented from entering the barrel of another coil by the open turn at the ends of the coils. The pitch of the additional open turns is such that the primary coil length and, thus, the electrical characteristics of the improved coils are substantially the same as that of a conventional coil.

A better understanding of the invention will be obtained from the accompanying drawing, wherein:

FIGURE 1 is a side elevational view on an enlarged scale of a prior art electrode used in rapid-start fluorescent lamps;

FIG. 2 is a cross-sectional view, on a greatly enlarged scale, through the leg portion of the coil along the reference line II—II of FIG. 1;

FIG. 3 is a side elevational view of a pair of such prior art rapid-start lamp electrodes that are interlocked in the manner characteristic of these coils;

FIG. 4 is a side elevational view of an improved electrode embodying the invention; and

FIG. 5 is a view corresponding to FIG. 3 illustrating the maximum degree of entanglement which can occur with the improved electrodes of the present invention.

While the invention is broadly applicable to various types of electrodes and devices, it is particularly adapted for use in conjunction with coiled-coil electrodes for rapid-start fluorescent lamps and has accordingly been so illustrated and will be so described.

Prior art design

In FIG. 1 there is shown a conventional type electrode 10 heretofore employed in fluorescent lamps designed for rapid-start operation. As shown, the electrode 10 comprises a coiled coil of refractory metal wire, such as tungsten, having a short barrel or body portion 12 that consists of approximately three secondary or major turns 14 and is terminated at each end by an axially extending substantially straight leg 16.

As shown more particularly in FIG. 2, the electrode 10 is formed in the well known manner by winding a fine tungsten wire 18 around a larger-dia metered tungsten core wire 20 to form a composite primary wire. This primary wire is then wound about a mandrel to form a primary winding or coil which is then coiled around another and much larger mandrel to form a coiled coil having the desired number of major turns 14 (see FIG. 1) and thus complete the electrode. The major turns are wound at a substantially uniform pitch and are, accordingly, evenly spaced. A detailed description of the manner in which such electrodes are fabricated and the manner in which the short barrel section and relatively long legs enable the lamp to start without the use of a high voltage transformer are set forth in the above-mentioned U.S. Patent No. 2,774,918 to Lemmers.

Since the length L_e (see FIG. 1) of the legs 16 of the prior art electrodes 10 are much longer than the length L_b of the barrel section 12, it frequently happens that another coil 10a becomes so aligned with the coil 10 that the legs of the respective coils protrude into the barrel of the other coil in the manner shown in FIG. 3. When this occurs the coils become interlocked to such a degree that they cannot work free when they are placed into the vibrating hopper of the coil-feeding unit and, accordingly, are unable to ride up the feeding track. Since the legs 16 and 16a of the respective electrodes 10 and 10a extend through and beyond the respective coil barrels 12 and 12a and press against the inner surfaces of the major turns 14 and 14a, there is little or no freedom of movement between the interlocked electrodes and the only way in which they can be separated is by manually forcing them apart.

As a specific example of the dimensions of the various portions of prior art type coils, a conventional electrode

designed for use in a 40-watt rapid-start fluorescent lamp generally has a coil barrel L_b (see FIG. 1) that is approximately 90 mils long, 60 mils in outside diameter and includes three major turns wound at about 33 turns per inch (TPI). The length L_e of each of the legs is approximately 250 mils. Thus, the legs are much longer than the length of the coil barrel and easily protrude into and through the barrel of another coil when the coils become entangled in the manner shown in FIG. 3.

The invention

As is shown in FIG. 4, the aforesaid coil-tangling problem is overcome according to the present invention by providing a modified electrode 22 that has a coil barrel 24 with the same number of secondary or major turns 26 as the above-described prior art electrodes but which is terminated at each end by an open turn 28 and by a very short leg 30. The additional end or open turns 28 are wound at a much greater pitch than the major turns 26 so that there is a relatively large spacing p between the axial-extending legs and the proximate ends of the coil barrel. By forming a portion of each of the legs into a single open turn in this manner, the legs are not only greatly reduced in length but are prevented from protruding into the coil barrel of another electrode by the respective open turns. The improved electrodes are, accordingly, inherently tangle-proof. The pitch p of the open turns is preferably made such that it is equivalent to about $\frac{3}{4}$ the length of the adjoining leg. Expressed differently, the length of each of the legs 30 is such that it is approximately equal to $1\frac{1}{3}$ times the pitch p of the adjoining open turn 28.

As a specific example of the relative dimensions of the various parts of the improved coils, in the case of an electrode for a 40 watt rapid-start fluorescent lamp the coil barrel 24 consists of three major turns wound at approximately 33 TPI and has a length L_b (see FIG. 4) of approximately 90 mils, as in the case of the prior art electrodes described above. Each of the open turns 28 are wound at approximately 13 TPI and thus has a pitch p (or an axial length) of about 75 mils. This is equal to a primary coiling length of about 150 mils. Each of the legs 30 have an axial length L_e of about 100 mils so that the length of primary coiling utilized in each leg and the adjoining open turn is about 250 mils, which is equivalent to that used in each of the legs of a conventional type electrode of the same rating. The improved electrode 22, accordingly, has approximately the same primary coiling length as the prior art electrodes and, thus substantially the same electrical characteristics. However, since the leg length is much shorter the overall length of the improved coil is also somewhat shorter, as will be noted from a comparison of FIGS. 1 and 4.

As shown in FIG. 5, even if the shortened leg 30 of one electrode 22 should become interlocked with the spaced end turn 28a of another electrode 22a, the degree of interlock is so minor compared to that encountered with the prior art electrodes that the coils very readily work free by themselves when vibrated in the hopper of the coil-feeding unit. Since only the open turn of each of the coils is engaged by the legs of the other coil, only a very small amount of relative movement between the electrodes will free them. Once free, the improved coils can proceed up the feeding track one at a time in the proper manner.

Moreover, the inherent instability of the prior art electrodes produced by the relatively short coil barrel and relatively long and heavy legs is also corrected by the present invention since the legs of the improved electrodes are relatively short and the open turns at each end of the medial coiled section or barrel provide additional points of contact with the surface on which the electrode rests. Thus, the improved electrodes do not wobble or tip as

they proceed up the vibrating feeding track and automatically align themselves on the track in a continuous row.

Conclusion

- 5 It will be appreciated from the foregoing that the objects of the invention have been achieved insofar as an improved electrode for a rapid-start fluorescent lamp or the like has been provided, which electrode is so designed that it can be shipped and handled in bulk without becoming tightly interlocked with other electrodes. In addition, the improved electrodes are more stable than those used heretofore and thus can readily be automatically fed along a track into a stem-making machine and mounted.
- 10 15 While one embodiment has been illustrated and described in detail, it will be appreciated that various modifications in both the configuration and dimensions of the various portions of the electrode can be made without departing from the spirit and scope of the invention.
- 20 25 30 We claim as our invention:
1. An electrode for an electric discharge device comprising a refractory metal wire coil having a medial coiled section, and an axially extending leg at each end that is joined to said coiled section by an open turn which is substantially aligned with said coiled section.
  2. The electrode set forth in claim 1 wherein, said medial coiled section comprises a plurality of turns wound at substantially the same pitch, and each of said open turns has a pitch greater than the pitch of the turns comprising said medial coiled section.
  3. The electrode set forth in claim 1 wherein the pitch of each of the open turns is equivalent to about $\frac{3}{4}$ the length of the adjoining leg.
  4. An electrode for an electric discharge lamp comprising a coiled coil of refractory metal wire having an elongated body portion of predetermined length that is terminated at each end by (a) an open turn that is aligned with said body portion and (b) a substantially straight leg that is shorter than said body portion and axially extends from said open turn.
  5. An electrode for a fluorescent lamp comprising, a first refractory metal wire wound into a coiled coil of linear configuration the major turns whereof are wound at a substantially uniform pitch, and a second refractory metal wire of smaller diameter wound around said first wire, said coiled coil being terminated at each end by an aligned open turn that has a pitch greater than the major turns which comprise the body portion of said coiled coil, and by a leg that extends axially beyond said open turn for a distance approximately equal to $1\frac{1}{3}$ times the pitch thereof.
  6. An electrode for a rapid-start fluorescent lamp comprising, a first refractory metal wire wound into a coiled coil of linear configuration having no more than four major turns that are wound at a substantially uniform pitch, and a second refractory metal wire of smaller diameter wound around said first wire at a substantially uniform pitch, said coiled coil being terminated at each end by an aligned open turn that has a pitch greater than the major turns which comprise the body portion of said coil, and by a leg that extends axially from and beyond said open turn for a distance approximately equal to $1\frac{1}{3}$ times the pitch thereof.
